(57) **CLAIM**

The ornamental design for a seating furniture as shown and described.

DESCRIPTION

FIG. 1 is a front, top, left perspective view of a first embodiment of the seating furniture showing our new design in a first configuration;

FIG. 2 is a front view thereof of FIG. 1;

FIG. 3 is a rear view thereof of FIG. 1;

FIG. 4 is a right side view thereof of FIG. 1;

FIG. 5 is a left side view thereof of FIG. 1;

FIG. 6 is a top view thereof of FIG. 1;

FIG. 7 is a bottom view thereof of FIG. 1;

FIG. 8 is a front, top, left perspective view of the embodiment of FIG. 1 shown in a second configuration;

FIG. 9 is a front, top, left perspective view of a second embodiment of the seating furniture;

FIG. 10 is a front view thereof in the embodiment of FIG. 9;

FIG. 11 is a rear view thereof in the embodiment of FIG. 9;

FIG. 12 is a right side view thereof in the embodiment of FIG. 9;

FIG. 13 is a left side view thereof in the embodiment of FIG. 9;

FIG. 14 is a top view thereof in the embodiment of FIG. 9; and,

FIG. 15 is a bottom view thereof in the embodiment of FIG. 9.

The parallel uneven length broken lines extending from the front to the back of the seating furniture define the bounds of the claimed design and form no part thereof, and the spacing therebetween forms no part of the claimed design. The even length broken lines represent features which form no part of the claimed design.
